Inventor:

Sidney M. Knapp,
By his Attorney,
Geo. McMath

UNITED STATES PATENT OFFICE.

SIDNEY M. KNAPP, OF NEW YORK, N. Y.

DESIGN FOR A DUPLEX SOCKET FOR ELECTRIC-LAMPS.

60,350.

Specification for Design.

Patented Feb. 7, 1922.

Application filed January 8, 1921. Serial No. 435,995. Term of patent 3½ years.

To all whom it may concern:

Be it known that I, SIDNEY M. KNAPP, a citizen of the United States, residing at the borough of Manhattan, city, county, and State of New York, have invented a new, original, and ornamental Design for a Duplex Socket for Electric Lamps, of which the following is a specification, reference being had to the accompanying drawing, forming part thereof

Fig. 1, is a side elevation of a duplex socket for electric lamps, showing my new design; and

Fig. 2, is a top view thereof.

I claim:

The ornamental design for a duplex socket for electric lamps, as shown

SIDNEY M KNAPP.
